(57) **CLAIM**

The ornamental design for a clip for covering a tooth, as shown and described.

DESCRIPTION

FIG. 1 is a perspective view of a clip for covering a tooth according to the present invention.

FIG. 2 is a front view of the clip for covering a tooth of FIG. 1.

FIG. 3 is a rear view of the clip for covering a tooth of FIG. 1.

FIG. 4 is a left side view of the clip for covering a tooth of FIG. 1.

FIG. 5 is a top view of the clip for covering a tooth of FIG. 1; and,

FIG. 6 is a bottom view of the clip for covering a tooth of FIG. 1.

A right side view thereof is omitted since it is a mirror image of the left side view.
